UNITED STATES PATENT OFFICE.

CHARLES J. VAN DEPOELE, OF CHICAGO, ILLINOIS.

SUSPENDED CONDUCTOR FOR ELECTRIC RAILWAYS.

SPECIFICATION forming part of Letters Patent No. 358,512, dated March 1, 1887.

Application filed October 19, 1886. Serial No. 216,607. (No model.)

To all whom it may concern:

Be it known that I, CHARLES J. VAN DEPOELE, a citizen of the United States, residing at Chicago, in the county of Cook and State of Illinois, have invented certain new and useful Improvements in Suspended Conductors for Electric Railways, of which the following is a specification, reference being had therein to the accompanying drawings.

10 The present invention relates to improvements in the arrangement of some of the parts of the system of "suspended electric railway conductors," shown and described in Letters Patent No. 344,425, granted to me June 29, 1886; and it consists in certain improved methods of arranging the cross-wires and supporting-cables on curves, whereby much greater stability of the curved portions of the conductor is secured, and it also relates to and

15 includes improved means of insulating the suspended conductor or conductors from their supports, as will be hereinafter fully set forth.

In the accompanying drawings, which form part of this specification, Figure 1 is a plan view of a portion of an electric railway arranged according to my invention. Fig. 2 is a view in elevation, on an enlarged scale, showing the supporting-cable, insulator, hangers, and the clamp by which the insulator is held in position. Fig. 3 is a longitudinal sectional elevation of the insulator. Fig. 4 is a cross-section thereof.

Similar letters denote like parts throughout.

A represents the curb-lines of intersecting streets, of which a are the sidewalks.

B are pole-pieces placed alongside the curb, and at suitable distances apart, on opposite sides of the streets traversed by the railway, and from their tops extend strong cross-wires 30 C, from which the electric conductor or conductors D, as the case may be, are suspended.

In order to give the curved portions of the conductor the requisite stability I provide the inner corner of a curve with a strong cable, d, 45 extending some fifty or one hundred feet in each direction from a pole, B', at the corner of the street, on the inside of the curve, to other poles, B², which should be somewhat stronger than the ordinary poles, B, to meet the greater strain put upon them. On the opposite side 50 from poles B', placed opposite the poles B²,

are stretched short cables d', extending to corner poles, B², from which a longer cable, E, extends, spanning the space between the intersecting streets on the outside of the curve. 55 A number of cross-wires, e, extend from the cables E and d' across above the curved portions of the conductor and are secured to the cables d, from which they spread out like the ribs of a fan.

F represent anchorage-rod that are secured to the conductor or conductors D, as set forth in my patent above referred to, said anchorage and tension devices being secured to the central insulator, f, which also 65 partially supports the cross-cable E, and from which extends the guy rod or cable G, which is secured to and supported by a pole, g, at the opposite street-corner.

H represents tubular insulators, which are 70 placed upon the cross-wires C and e, and from which the conductor or conductors are suspended by the hangers I, which consist of a longitudinally-divisible upper portion, i, from which depends an arm turned at right angles 75 at its lower end for the reception of a bail, J, supporting the conductor D.

The insulators H are formed by taking a tube, h, of iron, paper, wood, or other suitable material, of a size that will permit it to be 80 easily slipped onto the cross-wire by which it is supported. The tube h is provided with a tightly-wrapped covering, H', consisting of several layers of fabric thoroughly coated with asphaltum, shellac, varnish, or other reliable 85 insulating-compound, which is wound upon the tube while fresh, so that when dry a very strong and durable tubular insulator is produced, which, when placed in position upon the cross-wire, is capable of supporting one or 90

more of the hangers I, as indicated in Fig. 2, thereby insuring perfect insulation of the supported conductors, and at the same time adding to the strength and symmetry of the structure.

95 A clamp or clamps, K, are provided at one or both ends of the insulators H, and firmly secured to the cross-wires, thereby securing the said insulators in any desired position, and at the same time admitting of any desired 100 change being easily and quickly made. It will be noted also that the above-described con-

struction of the upper portion of the hanger renders it readily adjustable along the insulator H, to which it is secured.

Only one set of hangers is shown in Fig. 1, 5 since there is also only one conductor there indicated. In Fig. 2 is, however, shown an arrangement comprising a double set of hangers and conductors, the position to be occupied by a single hanger being indicated in dotted lines. 10 It will be obvious therefore that the insulator may be made in any desired length, and any number of sets of conductors supported therefrom. Other modifications will naturally suggest themselves, and I do not therefore desire 15 to limit myself to the exact details of construction shown.

What I claim, and desire to secure by Letters Patent, is—

1. In a suspended conductor for electric railways, the combination of a supporting cable or cables extending along the inside of the curve, a similar cable extending across from corner to corner on the outside of the curve, and two or more cross-wires extending between the 20 supporting-cables and provided with suspending devices upon which the conductor is supported, substantially as shown and described.
2. In a suspended conductor for electric railways, the combination, with supporting-cables 25 extending along the inside of the curve, a similar supporting-cable extending across from corner to corner on the outside of the curve, and additional end portions extending along the curve on the outside of the curve, and cross-wires extending between the supporting-cables 30 across above the curved portions of the conductor, and provided with suitable suspending devices by which it is supported therefrom, substantially as shown and described.

3. An insulator for electric railways, consisting of a tube enveloped on its exterior with a covering or wrapping consisting of sheets of insulating material, a supporting wire or cable passing through said tube, and means, substantially such as described, for suspending the 40 working-conductor therefrom.

4. An insulating-support for electric-railway conductors, consisting of a metallic tube covered on its outside with a wrapping of insulating fabric forming a solid body and detachable and adjustable supports arranged to carry electric conductors, and affixed thereto, as described.

5. The combination, with suitable supporting wire or cable and a tubular insulator 55 through which the supporting-cable passes, of an adjustable clamp secured to the said support for holding the insulator in the desired position, substantially as shown and described.

6. The combination of suitable supporting 60 wire or cable, the tubular insulator upon said support, and the two-part detachable and adjustable hanger I, secured upon said insulator, substantially as shown and described.

7. The combination, with suitable cross-wire, of the tubular insulator, the clamp for securing the same in position, and the adjustable hangers I, substantially as shown and described.

In testimony whereof I affix my signature in 70 presence of two witnesses.

CHARLES J. VAN DEPOELE.
